UNITED STATES PATENT OFFICE.

CLARENCE LORAN JOHNSTON, OF OAKLAND, CALIFORNIA, ASSIGNOR TO AMERICAN SALES BOOK COMPANY, LIMITED, OF TORONTO, ONTARIO, CANADA, A CORPORATION OF ONTARIO, CANADA.

SUPPLY PAD FOR AUTOGRAPHIC REGISTERS.

Original application filed February 23, 1924, Serial No. 694,458. Divided and this application filed December 30, 1924. Serial No. 758,820.

This invention relates to improvements in record strips such as are employed in autographic manifolding registers, and more especially to an improved zigzag supply pad 5 for autographic registers including such record strip. The subject matter of this application is divided from a prior application for autographic registers, filed February 23, 1924, Serial No. 694,458.

10 It is an object of the invention to provide an improved supply strip for use in registers of the class mentioned which is especially formed and adapted to cooperate with operative elements of the register to aid in placing the strip in filing position.

Another object is to provide an improved manifolding supply pack for insertion in the supply magazines of registers of the class mentioned, the record strips whereof are 20 especially formed for aligning the strips, and one or more of the strips being formed for positive cooperation with an element of the register for direction into a compact filing or storage pad.

25 Other objects will be in part pointed out in connection with the following detailed description of an illustrative but preferred embodiment of the invention, and will in part be obvious in connection therewith.

30 According to this invention a supply pad for autographic manifolding registers is made up of one or more record strips folded together in zigzag formation into a compact easily handled supply pad which may be 35 readily inserted in the magazine of the register. In connection with the operation of machines of the character mentioned, it will be understood that a plurality of record strips may be simultaneously fed from storage position into position for receiving an entry, such as an autographic record of a sale, the record being transferred from the original record-receiving strip to the other record-receiving strips by means of a carbon or

40 similar transfer strip. As it is often desirable to preserve in good condition one or more of the record strips with its impressed record, and secure it from unauthorized access, the invention contemplates providing a file strip with formations such as apertures arranged at intervals and positioned for cooperation

with the machine to positively direct the strip into compact filed position in a closed compartment of the register. These filing or folding apertures are arranged in series 55 so that only predetermined parts of the file strip will be selected and the strip thus folded in a zigzag filing pad in accordance with the folds or creases of the original supply pad. Form-aligning apertures are also preferably employed in all the record strips for cooperation with feed rolls or discs of the register so as to cooperate with said discs to effect longitudinal alignment of the strips, 60 thus to bring the blank forms affixed thereon 65 into exact registry.

For a more complete understanding of the nature and objects of the invention, reference is had to the accompanying drawing showing a preferred embodiment of the invention, and in which,

70 Figure 1 is a perspective view of a fragment of a supply pad made up of three record strips, one of which is formed for automatic filing, parts being broken away for clearness of disclosure, and the strips being shown as slightly separated to facilitate disclosure;

Fig. 2 is a plan view of a fragment of a filing strip, constructed in accordance with 80 the invention;

Fig. 3 is a longitudinal vertical section disclosing a form of autographic register adapted to utilize the improved supply pad;

Fig. 4 is a fragmentary view disclosing 85 operative parts of the register and their relation to a record strip being filed in a compartment of the register; and

Fig. 5 is a view similar to Fig. 4, but showing the operative parts of the register in a 90 different position.

Referring to the drawing for a complete description of the embodiment of the invention there shown, a fragment of a supply book or pad is shown in Fig. 1, being indicated generally by the reference numeral 10. This supply pad as shown, includes triplicate record strips 11, 12 and 13 folded into the pad in zigzag formation. Each of the strips is weakened along transverse lines as indicated at 14, so as to diminish resistance of the strip to folding along these lines.

This weakening may be accomplished in different manners, such as by a line of small perforations, by creasing, or by similar deformation of the strips. Also combinations 5 of the different methods of weakening the strip against folding resistance may be employed, for example, as illustrated in the drawing, by both perforating and creasing the strips. These perforations not only assist 10 in folding the strips in a compact and smooth zigzag pack, but they are also useful in severing the strip along the weakened lines for detaching a section of the strip containing one or more of the blank forms.

15 As will be understood, the successive deformations of the record strips employed in the zigzag pack engender in the strips folding tendencies in opposite directions. This folding tendency in the file record strip as 20 consists in refolding the strip again into zigzag position by operation of the register, after a record has been impressed upon the strip. The deformations divide each strip into a series of attached sheets or pad leaves, des- 25 ignated in the respective record strips by 11^a, 12^a, and 13^a, each bearing one or more blank forms 15, printed or otherwise affixed or compressed thereon. Each pad leaf is pro- 30 vided with form-registering or feed-control- ling apertures 16, preferably disposed at the forward end of each blank form, or so as to bear a definite relation thereto. These apertures are arranged in longitudinal series 35 in the strip, each series being positioned in each strip for alignment with the feed rolls or discs of the register in which the record strips are employed. Each pad leaf is shown in the drawing as provided with a single blank form, but if two or more forms are 40 desired for each leaf, it will be understood that additional form-registering apertures may be provided. The length of record strip occupied by each blank form may be termed a form sheet or ticket, as distinguishing it 45 from the pad leaf 11^a, 12^a or 13^a.

One or more of the record strips may be prepared for automatic filing in a compartment of the register as suggested. For example, the strip 11 indicated in the drawing 50 is intended to be so filed after a record has been made thereon. In order to co-operate with a filing or folding mechanism carried by the register, the storage record strip is specially formed, as shown in detail in Fig. 55 2, each alternate pad leaf 11^a being provided at or near its forward or leading end with a filing or fold-directing formation such as an aperture 17, these apertures being ar- 60 ranged in series longitudinally of the record strip and spaced respectively laterally from the adjacent form registering apertures 16. The fold-directing apertures 17 are similarly disposed in the different pad leaves with reference to the adjacent fold lines 14 so 65 as to properly cooperate with the folding

mechanism of the machine. The alternate pad leaves, intermediate those having the fold-directing apertures 17, are imperforate at points corresponding to the fold-directing apertures. 70

As shown in Fig. 1 one or more of the strips 12 and 13 may be provided also with filing or fold-directing apertures, 17, so these strips may be filed, if desired, but such apertures are needed only in strips to be filed. 75 If all the strips are provided with filing apertures, the strip or strips intended for filing may be selected by the manner of initial threading into the register.

The general arrangement of an auto- 80 graphic register adapted for utilizing the improved supply pad is shown in Figs. 3, 4 and 5, which will be sufficient to disclose the method of using the improved supply strip and pad in such a machine. Inasmuch 85 as the machine per se is not claimed herein, it is not necessary to describe it in full detail, reference for such a description being had in the co-pending application above referred to.

As herein shown, the register casing 20 89 is divided by a transverse partition 21 into interior compartments 22 and 23 for respec- 95 tively receiving the supply pad 10, and the storage pack or pad 10^a. The strips 11, 12 and 13 are led from the supply pad 10 re- 100 spectively over strip guides 24, 25 and 26 through an opening in the upper part of the casing to overlie a writing table or platen 27. While in position on the platen to re- 105 ceive an entry, a transfer strip or strips, such as carbon paper, will be supported in position between adjacent record strips, as will be understood by those skilled in the art.

Beyond the writing table, the strips are 110 led between and gripped by an upper feed roll 28 and a pair of spaced feed discs (not shown) mounted on a feed shaft 29 and spaced apart a distance equal to the lateral distance between adjacent form-aligning 115 apertures 16 in the record strips. The roll 28 being pressed against the feed discs, the strips will be advanced by rotation of the latter, until the form-aligning apertures of the several record strips come into registry 120 with the bite between the roll 28 and the feed discs, when feeding action of the re- 125 spective strips will be checked. Feeding action of any strip which may be lagging behind the others will be continued until all the form-aligning apertures come into reg- 130 istry in the bite of the feed roll and discs when the blank forms on the several strips will be in superposed alignment so an entry of a record made on the form of the top strip 13 will be transferred in correct reg- 135 istry with the forms of the underlying strips.

A disc 30 or similar carrying member is mounted on the feed shaft 29 for rotation therewith, being slightly smaller than the 130

feed discs, so as not to exert any considerable gripping or feeding action upon the record strips disposed therebetween and the roller 28. A folding finger 31 having a strip engaging projection 32 is eccentrically pivoted upon the disc 30 as at 33 and is biased to forwardly projecting position by a spring 34. This finger is also provided with an operating pin or lug 35 extending through 10 a slot in the disc 30 and lying in position to co-operate with an operating cam 36 carried in stationary position by the casing. The cam is provided with an inclined operating surface 37 and with a curved operating surface 38 concentric with the axis 29, for co-operation with the lug 35. During one complete revolution of the feed shaft 29, the strips are fed forwardly a distance equal to that between two successive form-aligning 15 apertures 16.

In Fig. 3, the strip 11 is shown as being folded in stored position in the storage compartment 23, while strips 12 and 13 are directed to a position overlying the cover part 25 39 of casing at the rear of the roll housing and support 40, where they may be conveniently severed by pulling them across the cutting edge 41 of the support 40. Severance of the strips may be also facilitated by 30 the weakened line 14. It will be understood, however, that more than one of the record strips may be automatically filed away by operation of the machine, provided, of course, each filed strip is provided with the 35 required filing apertures 17, and is properly initially threaded into the register in the position of the strip 11 shown in Fig. 3.

As the disc 30 rotates, the folding finger 31 is moved inwardly by contact of the lug 35 with the inclined cam surface 37 and is held in retracted position when the lug engages the concentric cam surface 38. When the lug 35 passes beyond the cam surface, the folding finger is urged forwardly by operation of the spring 34. If a folding aperture 17 is present as indicated in Fig. 3, the finger projection 32 enters the aperture carrying the strip around with it until the finger is again retracted by engagement of the 50 lug with the cam face 37, whereupon the strip is released. As the strip is carried around by the folding finger, it is doubled and folded along the weakened line 14, the fold being released to assume folded position adjacent the partition 21. In case one of the pad leaves without the folding aperture 17 lies adjacent the folding finger 31 when the latter is released by its cam, the finger contacts with the surface of the paper and moves around idly, as shown in 55 Fig. 5.

In this case, the result is that the portion of the strip where the feed aperture is absent is projected into the rear of the compartment forming a fold at the weakened 60

part of the strip at the opposite or rear end of the storage pack 10^a. The transverse weakened line 14 again enables the strip to lie flat in compact folded position. Thus the folding finger acts positively to direct 70 predetermined parts of the filing strip to folded position at one end of the filing pack. It will therefore be seen that a record strip and supply pad constructed as described may be laid in a compact zigzag pack 75 or pad in the compartment, where it may be preserved free from unauthorized access. Any of the leaves may be filed away by means of the form registering apertures 16, which are conveniently positioned in each 80 leaf for the reception of filing posts or similar supports. In the embodiment illustrated, the intervals between successive fold-directing apertures 17 are greater than those between successive of the transverse weakened lines 14, so that the fold-directing finger will positively engage and fold alternate pad-sheets. But the intervals between successive form-registering apertures may 85 be, and in the embodiment illustrated are, 90 less than those between successive fold directing apertures, so that two or more registrations may be effected between two successive operations consequent from the fold-directing apertures. 95

Since certain changes may be made in the above article and different embodiments of the invention could be made without departing from the scope thereof, it is intended that all matter contained in the above description or shown in the accompanying drawing shall be interpreted as illustrative and not in a limiting sense. 100

It is also to be understood that the following claims are intended to cover all of 105 the generic and specific features of the invention herein described, and all statements of the scope of the invention which, as a matter of language, might be said to fall therebetween. 110

Having described my invention, what I claim as new and desire to secure by Letters Patent is:

1. A supply record strip for record-making machines having blank forms thereon forming a longitudinal series of form sheets, the strip being provided with fold-directing formations arranged in series on the strip and being spaced apart distances greater than the length of the form sheets. 115

2. A supply record strip for record-making machines having blank forms thereon forming a longitudinal series of form sheets, the strip being provided with fold-directing formations arranged in series on the strip and being longitudinally spaced apart distances approximately the same as the combined lengths of two form sheets, the strip being weakened at intervals on transverse 120 lines and having form-registering apertures 125

therein bearing a definite relation to each of the blank forms and forming a series spaced from the series of folding formations.

3. A record strip including successive pad leaves and having weakened transverse lines between adjacent successive pad leaves upon which the strip is adapted to fold in opposite directions, the record strip having filing apertures arranged in a longitudinal series 10 and spaced apart distances approximately equal to the combined lengths of two pad leaves and positioned in the vicinity of the respective weakened lines and being adapted to cooperate to direct the folding in the 15 same direction of said alternate successive pad leaves around the adjacent weakened lines.

4. A storage record strip having a series of record forms dividing the strip into a 20 series of record sheets, and being provided with a series of form-aligning apertures and a series of storing apertures, the latter being for use in directing the strip into filing or storage position, and being formed only 25 in alternate record sheets.

5. A supply pad for manifolding machines, including a record strip folded in zigzag formation in the pad, forming pad leaves between adjacent folds and having re- 30 folding formations including a longitudinal series of selecting apertures positioned only in alternate pad leaves and adapted to cooperate when fed in the register to cause the pad leaves of the strip to refold into a zigzag pad with adjacent leaves folded in the 35 same direction relative to each other as in the supply pad.

6. A supply pad for manifolding machines, including, in combination, a plurality of record strips folded zig-zag and having interengaging folds so as to provide superposed sets of superposed leaves connected end to end, each alternate leaf in one of said strips having a filing aperture adapted to cooperate with the machine to direct 45 folding of said apertured strip into filing condition, the intermediate alternate leaves of said apertured strip, at points corresponding to said directing apertures, being imperforate.

7. A supply pad for manifolding machines including, in combination, a plurality of record strips folded zigzag, the folds of one interengaged with those of the others 55 so as to provide superposed sets of superposed leaves connected end to end and having blank forms thereon, the fold lines in each strip being weakened as to resistance to strip folding, each strip having a longitudinal series of form-registering apertures 60

in fixed relation to said forms, respectively, one or more of said strips having additional directing apertures adapted to cooperate to direct folding of the leaves around adjacent weakened lines.

8. A supply strip for autographic registers having a longitudinal series of pad leaves attached end to end and forming a longitudinal series, the strip being weakened as to folding resistance on transverse lines between adjacent pad leaves and being provided with fold-directing formations arranged in series in the strip, said fold-directing formations being disposed similarly in different pad leaves with reference to the respective adjacent weakened lines.

9. A supply pad for manifolding machines including, in combination, a plurality of record strips folded zigzag, the folds of one interengaged with those of the others 80 so as to provide superposed sets of superposed leaves connected end-to-end and having blank forms thereon, the fold lines in each strip being weakened, as to resistance to strip folding, each strip having a longitudinal series of form-registering apertures, each having a predetermined relation to each respective form, one or more of said strips having additional strip-directing apertures arranged in longitudinal series in the strip and longitudinally spaced apart distances approximately twice the longitudinal spacing of said weakened fold lines, said strip-directing apertures being adapted to cooperate to direct the folding of said alternate 85 leaves always in the same direction around the adjacent weakened lines.

10. A record strip folded zig-zag and having weakened lines coincident with the lines on which it is folded zig-zag, said strip having a longitudinal series of fold-directing apertures, the intervals between successive of said fold-directing apertures being greater than those between successive of said weakened lines.

11. A record strip folded zig-zag and having weakened lines coincident with the lines on which it is folded zig-zag, said strip having a longitudinal series of fold-directing apertures, and a longitudinal series of form-registering apertures, the intervals between successive of said fold-directing apertures being greater than those between successive of said weakened lines, the intervals between successive of said form-registering apertures being less than those between successive of said fold-directing apertures.

In testimony whereof I affix my signature.

CLARENCE LORAN JOHNSTON.
